UNITED STATES PATENT OFFICE.

ROLLIN A. BALDWIN, OF NEW HAVEN, CONNECTICUT, ASSIGNOR TO THE BALDWIN & ROWLAND SWITCH & SIGNAL COMPANY, A CORPORATION OF CONNECTICUT.

CIRCUIT-CONTROLLER.

SPECIFICATION forming part of Letters Patent No. 783,715, dated February 28, 1905.

Application filed September 29, 1904. Serial No. 226,489.

To all whom it may concern:

Be it known that I, ROLLIN A. BALDWIN, a citizen of the United States, residing at New Haven, in the county of New Haven and State of Connecticut, have invented certain new and useful Improvements in Circuit-Controllers, of which the following is a full, clear, and exact description.

This invention relates to circuit-controllers for overhead-trolley electric-railway systems, and involves the application of a shoe or frame to the trolley-wire for the purpose of deflecting the current through a local circuit or circuits whenever a trolley-wheel passes over the device.

The object of the invention is to provide a device of this character which shall be simple and cheap to construct, easily and quickly applied to the wire without severing the same, and which will operate without the production of an excessive spark.

The invention consists of the constructions and combinations thereof hereinafter described, and particularly pointed out in the claims.

In the accompanying drawings, Figure 1 represents a plan of my improved contact device. Fig. 2 is a reversed plan of the same. Fig. 3 is a side elevation. Fig. 4 is a transverse section, and Figs. 5 and 6 illustrate two different arrangements of circuits controllable by my improved device.

The trolley-wire is indicated at *a*, which, as usual, is supplied with current by a feeder *b*, connected at intervals therewith by branch conductors *c*. The device constituting my invention consists of a two-part insulating-base *E*, the members of which are indicated by *e* and *e'*. This base is preferably of wood, but may be of any other suitable insulating material. It is elongated in shape, and its members are joined together at the middle on a longitudinal vertical plane and are secured together by means of transverse bolts *f*, any suitable number of which may be used. The extremities of this base are inclined in opposite directions on the under side. The abutting surfaces of the members *e* and *e'* are formed with opposed grooves, semicircular in

cross-section and together forming a passage 50 through the insulating-base for the trolley-wire *a*. This passage leads outward at each end of the structure through the inclined face thereof, so that through the body portion the passage is sunken into the base and the 55 wire when located therein is not exposed at its under surface. Attached to the under surface of the base and arranged in a longitudinal position thereon, one upon each side of the passage for the wire, are two metallic plates 60 *g* and *g'*, having depending side flanges, together forming a gutter or passage for the trolley-wheel. These plates are deflected at their extremities, as shown at *g*², to extend along the upwardly-inclined faces of the base 65 and obliquely across the line of the wire and at their extreme ends flare apart slightly to freely admit the trolley-wheel to the space between the flanges when it encounters the device in its passage along the wire. These 70 plates are secured to the base by means of screws *g*³ or in any other suitable manner and form a two-part track adapted to receive the two rims or flanges of the trolley-wheel. I prefer to mount these two plates in such a 75 manner that there will be a slight longitudinal space between their abutting edges, as shown in the drawings, and they are to be entirely disconnected and separate from the trolley-wire. Hence the passage or groove for the wire is 80 formed sufficiently deep in the base to prevent contact between the wire and the plates. The space between the plates is, however, ordinarily less than the diameter of the wire, so that they slightly overlap the wire and require to 85 be cut away in the regions where the wire emerges through their inclined faces, as shown in Fig. 2 at *h*. This contact device may be connected in the circuit in either of two ways. The two plates *g* and *g'* may be electrically 90 connected together by bridging the binding-posts *i* *i'*, respectively, connected with said plates by a connecting-wire *j*, as shown in Fig. 1, and then connecting one of said posts with the source of current-supply, or the 95 two posts *i* and *i'* may be used to connect two wires, which extend from them, respectively, to the source of supply.

The device is operated in the following manner: When it is desired to actuate a signal by means of the trolley-current and automatically by the moving car or train, one of the devices 5 herein described is placed upon the trolley-wire at the point where the signal is to be operated. The signal will be connected in the branch circuit leading from the feeder b to the circuit-controlling devices. Such a signal is 10 indicated at s in the branch circuit o . Now it will be seen that when the trolley-wheel (indicated by t) encounters one of the circuit-controlling devices its flanges strike, respectively, upon the inclined ends g^3 of the plates g and g' and the wheel is depressed until it leaves the wire entirely and thereafter runs along the horizontal portions of the two plates. During the passage of the wheel over the plates the current to propel the car is drawn 15 20 from the feeder b by way of the branch circuit o , containing the signal s , through the two plates g and g' and through the trolley-wheel and car, thus actuating the signal. In place of a signal an electromagnet for throwing a 25 switch in the rails upon which the car travels might be used, or, in fact, any other device to be operated by the trolley-current may be inserted in the branch circuit in the manner described, the device s thus representing any 30 such apparatus. If it is required that two different signals or devices be simultaneously actuated by the same circuit-controller, the wiring arrangement shown in Fig. 6 will be utilized, wherein s represents one signal or device 35 connected in a branch o from the feeder leading to one of the binding-posts i i' and the lamp or other device s' connected in an independent branch o' leading from the same feeder to the other post i i' . The two devices 40 to be actuated may be signals at opposite ends of a block, or one switch and one signal, or any other arrangement of devices appropriate to the invention. When the trolley-wheel passes over the two plates g and g' , the 45 current to propel the car will be drawn through both of the branches o and o' and actuate both of the devices s and s' . It will then unite at the trolley-wheel and flow through the car.

In the various forms of devices heretofore 5 provided for similar purposes great difficulty has been experienced by reason of the excessive sparking when the trolley-wheel strikes and leaves the device. In the present instance it will be seen that upon approaching 55 the circuit-controller the wheel does not leave the wire until its flanges are in good contact

with the plates g and g' , for it is by reason of that contact and the inclined arrangement of the plates that the wheel is caused to leave the wire. Likewise in passing from the circuit- 60 controller the wheel does not leave the plates g and g' until it is caused to do so by reason of its renewed contact with the trolley-wire. Hence the sparking that occurs at the making and breaking of the branch circuit or circuits 65 is reduced to a minimum. It will also be seen that this device may be very readily applied to the wire, since it is in two parts, which merely require to be placed upon opposite sides of the wire and clamped together by the 70 bolts described. It can also be adjusted to different positions along the wire by slackening the nuts on the bolts and sliding the device along the wire without entirely removing it. The side flanges on the plates g and g' prevent 75 displacement of the wheel in its passage over the circuit-controller.

Having described my invention, I claim—

1. A circuit-controller for trolley-wires, consisting of an insulating-base in two parts 80 adapted to be clamped together, the abutting surfaces of said parts being provided with opposing longitudinal grooves forming a passage for the trolley-wire and an external longitudinally-arranged contact-plate having portions at each end arranged oblique to said 85 passage and extending across the line thereof, for the purpose set forth.

2. A circuit-controller for trolley-wires, comprising an insulating-base containing a 90 passage for the trolley-wire and having an external longitudinal contact-surface arranged below the plane of the wire and having upwardly-inclined ends extending beyond the line of the wire, said inclined ends being cut 95 away to permit the wire to pass through them without touching, substantially as described.

3. A circuit-controller for trolley-wires, comprising an insulating-base adapted to be applied to the wire and carrying two contact- 100 plates, branch circuits leading from a source of electrical supply to the respective contact-plates and devices to be electrically actuated located in said branch circuits, substantially as described.

In witness whereof I subscribe my signature in the presence of two witnesses.

ROLLIN A. BALDWIN.
